UNITED STATES PATENT OFFICE.

JAMES F. COCHRAN, OF JONESBORO, TENNESSEE.

FRictional GEARING.

1,187,263.

Specification of Letters Patent. Patented June 13, 1916.

Application filed October 25, 1915. Serial No. 57,808.

To all whom it may concern:

Be it known that I, JAMES F. COCHRAN, a citizen of the United States, residing at Jonesboro, in the county of Washington 5 and State of Tennessee, have invented new and useful Improvements in Frictional Gearing, of which the following is a specification.

This invention relates to improvements in 10 gearing to reversely drive a driven element and more especially with reference to improvements in driving gears for the wringer rolls of washing machines and by means of which the wringer rolls may be driven by 15 power and may be stopped and reversed as desired.

The invention consists in the construction, combination, and arrangement of devices hereinafter described and claimed.

20 In the accompanying drawings:—Figure 1 is a side elevation of the wringing mechanism and driving gear of a washing machine constructed and arranged in accordance with my invention. Fig. 2 is a vertical 25 sectional view of the same through the wringer rolls and on the plane indicated by the line A—A of Fig. 1. Fig. 3 is a plan of the same. Fig. 4 is a vertical sectional view of the same on the plane indicated on the line B—B of Fig. 1. Fig. 5 is a similar view on the plane indicated by the line C—C of Fig. 1.

The wringing mechanism and driving gear thereof is adapted for use on a Peerless washing machine or in connection with other forms of washing machines. The base 1 has a bore or bolt of suitable length and breadth and is provided with clamps 2, 3, for securing the same on the tub or body 40 of a washing machine, each of the clamps comprising a bolt and the clamp 3 being movable in a slot 4, according to the diameter of the tub, and being provided with a thumb nut 5.

45 A pair of standards 6 are secured at suitable points on the base and are each provided with vertical slots 7 and also with vertical bores 8 which are intersected by the slots. An upper longitudinal corrugated 50 roll 9 has its shaft 10 mounted in bearings in the standards 6 and also has a ball-bearing 11 in a standard 12. Lower wringer rolls 13 are provided, of which there are three as here shown, said rolls 13 being 55 smooth or plane on their peripheries and having spindles 14 at their ends which are

arranged for vertical movement in the slots 7 and also have bearings in a pair of vertically movable bearing elements 15 which are arranged on the opposing sides of the standards 6. Springs 16 are arranged in the bores 8 and bear under blocks 17 in said bores and in which the spindles of the rolls 13 are also mounted, said springs moving the rolls 13 upwardly and causing them to compress articles of clothing or the like between them and the upper roll for wringing said articles by passing them between the opposing wringer rolls as will be understood. On the inner end of the shaft 10 is a friction disk 18.

A standard 19 which is fixed is at the outer end of the base 1 and at a suitable distance from the standard 19 is a standard 20 which has a vertical centrally arranged pivot 21 at 75 its lower end mounting the said standard 20 on the base for angular movement with reference to the ends of the friction disk. A transversely arranged shaft 22 is mounted in bearings 23 on the standard 20 and is provided at its ends with friction pulleys 24, 25 either of which may be engaged with the friction disk, said pulleys being opposed to opposite sides of said disk, as shown in Fig. 3. A bevel gear 26 is secured on the shaft 22. A longitudinally arranged shaft 27 is mounted in a bearing in the standard 19, is provided with a belt or power pulley 28 and is also provided with a bevel gear 29 which is engaged with the gear 26 so that the shaft 22 is driven by the shaft 27. A lever 30 is secured on the upper end of the standard 20 and extends from one side thereof and is grasped by the operator. By turning the lever and hence the standard 20 in one direction, or the other, either the friction pulley 24 or the friction pulley 25 may be engaged with the friction disk and hence the friction disk and the wringer rolls may be driven in either direction and readily reversed. By turning the standard 20 to a position exactly parallel with the friction disk, both of the friction pulleys may be disconnected from the friction disk to stop the operation of the rolls while permitting the shaft 27 to continue to be driven by its pulley and a power belt.

While I have herein shown and described a preferred form of my invention, I would have it understood that changes may be made in the form, proportion, and construction of the several parts without departing

from the spirit of the invention and within the scope of the appended claim.

Having described the invention, what is claimed is:

- 5 In gearing of the class described, a base, fixed standards on the base, a driven element having a shaft mounted in bearings in the standards and provided at one end of its shaft with a friction disk, a fixed 10 standard, a standard mounted for angular movement with respect to the disk and arranged between the disk and the fixed standard, a shaft in line with the driven element shaft and having bearings in said 15 fixed standard and said movable standard, said shaft being also provided with a power wheel and with a beveled gear, a

shaft arranged at right angles to the pivotal axis of the movable standard, having bearings in said standard and provided at 20 its ends with friction pulleys opposed to opposite sides of the disk and either of which may be engaged with the disk, a beveled gear on said shaft engaging the first named bevel gear, and a lever attached 25 directly to said removable standard and arranged to actuate the same.

In testimony whereof I affix my signature in presence of two witnesses.

JAMES F. COCHRAN.
